ABSTRACT: A resting place for a ladle, a knocking off station for knocking off a refractory covering from said stopper rod, a drying kiln provided with a rod-circulating device, and a receiving portion of an inclined guide leading into said drying kiln are disposed within a range in which a rod-handling device is horizontally and vertically movable. The installation further comprises adjacent to said guide a rod-straightening station and a station for applying a refractory covering to said stopper rod.

**INSTALLATION FOR REMOVING A STOPPER ROD
FROM A LADLE, APPLYING A NEW COVERING TO SAID
STOPPER ROD AND REINSERTING THE STOPPER ROD
INTO THE LADLE**

It is known that molten steel is poured from steel-casting ladles, which are lined with refractory material, and the molten steel flows through a tap brick which is provided in the bottom of the ladle. The velocity and rate at which the molten metal is poured are controlled by a stopper rod, which closes or exposes the opening in the tap brick. The stopper rod is provided with a refractory covering of tubular bricks, which must be renewed after each charge. For that purpose, it has been usual before to place the ladle on a tilting stand until its temperature has been lowered sufficiently to enable the covering of the stopper rod to be knocked off by hand. In order to reduce the cooling down time, water is often sprayed into the ladle although the sudden temperature change which then results will reduce the life of the ladle lining. In spite of such measures, workmen are exposed to the still high temperature of the ladle.

In very large steel-casting ladles, the stopper rods have a length of 4 meters and more and a heavy weight of about 200 kilograms so that it is fairly difficult to apply the bricks for the rod covering. This operation is carried out in most cases in a the tubular-covering bricks are threaded onto the stopper rod from a platform which is about 4-meters high, and the bricks are then lowered and caught by hand on the bay level. The covered stopper rods are carried by a usual crane to a drying kiln and when dry are returned to the ladle.

The crane must be controlled most carefully when the stopper rods are inserted into the conveyor chain of the drying kiln and when the finished stopper rods are inserted into the ladle.

It is an object of the invention to eliminate these disadvantages and to provide an installation which enables the operations required to remove, cover and insert the stopper rods to be performed with a high degree of mechanization.

The installation according to the invention is essentially characterized in that a rod-handling device is provided, which consists of a platform which is movable up and down on and pivotally movable about a column, a resting station for a ladle, a station for knocking off the covering, a drying kiln provided with a rod-circulating device, and the receiving end of an inclined guide rail or the like leading into the drying kiln are provided within the range of said platform, and a rod-straightening station and a station for applying a covering to the stopper rod are provided at said guide rail. The used stopper rod which is disposed in the resting ladle is released from the rod guide provided at the ladle and by means of the rod-handling device is lifted from the ladle and moved in one operation to the station for knocking off the old covering. In that station, the old covering is knocked off. When the used covering has been removed, the handling device transfers the bare stopper rod onto the guide rail, on which the rod reaches the additional working stations. The rod first reaches the rod-straightening station, where it is straightened by hand or machine if this is required. The rod is then applied back onto the guide rail and moves along the same to the station where the covering consisting of fresh-covering bricks is applied and where the rod is provided at its tip with a stopper brick. From the last mentioned station, the guide rail leads directly into the drying kiln, in which the rod-circulating device engages the arriving stopper rods provided with a fresh covering and circulates them within the kiln. By the rod-handling device, the finished stopper rod is carried from the kiln back to the ladle and inserted into the ladle. The entire installation may be disposed outside the range of the ladle crane and it is sufficient if the range of the pivotal movement of the platform extends into the range of said crane. The need for manual work is minimized because the movement of the stopper rod from the ladle through the several working stations to the drying kiln and from the latter back to the ladle is performed automatically and does not involve control difficulties and the operations in the working stations can be mechanized in a high

degree. In any case it is no longer necessary to perform the required operations by means of a crane, which can perform exact movements only with difficulty.

To facilitate the movement of the stopper rods along the guide rail, trolleylike roller blocks are provided according to the invention and adapted to be secured to the upper end of respective stopper rods. These roller blocks are secured to the stopper rods when the latter are still within the ladles. The handling device then engages the stopper rod below the roller block and is operated to apply the roller block and the rod suspended from it to the inclined guide rail so that the further movement is then automatically performed in that the roller block rolls down along the guide rail.

In a development of the invention, the roller blocks are adapted to be fitted onto the end portions of the stopper rods and to be fixed by a spring-loaded locking bolt, which is mounted in the roller block and adapted to snap into a transverse bore or the like in the rod. The upper end portion of the stopper rod is liable to be soiled by splashes of molten steel or molten slag. For this reason, a threaded joint or the like between the roller blocks and the rod end portions would not be desirable. The plug joint provided according to the invention is not affected by foreign matter. The locking bolt may readily be provided with an inclined runup surface so that it will be automatically forced back against spring force when the roller block is placed onto the rod end portion and the locking bolt will not move into its locking position until it has reached the transverse bore or the like of the rod. This will simplify also the manipulations required to secure the roller blocks to the rod end portions. When the newly covered stopper rod has been inserted into the ladle, it is sufficient to pull the locking bolt out of the bore or the like in the rod against the spring force and to remove the roller block from the end portion of the rod.

In accordance with the invention, barriers which intercept the roller blocks and which are preferably operable by cylinder-piston units are provided at the guide rail before the rod-straightening station, the station for applying the covering to the rod and the entrance to the kiln. By these barriers, the roller blocks which carry the stopper rods are held before the respective working station and can accumulate so that each rod can be handled alone and cannot bypass a working station. A simple control will be enabled if the barriers are operated with the aid of hydraulic or pneumatic cylinder-piston units.

The roller blocks are preferably provided with rubber buffers or the like on their leading and trailing end faces. These rubber buffers serve to prevent excessively hard impacts of the roller blocks as they roll along the guide rail and are intercepted by the barriers because such impact might throw the roller blocks from the rail.

It is also a feature of the invention that a point is provided where the guide rail enters the drying kiln. The rod-circulating device of the drying kiln consists, as a rule, of a suitable rail and a conveyor chain which is parallel to the latter rail and provided with driver flights. When stopper rods in the kiln should not be removed after one circulation but perform a plurality of circulations, the point is required to selectively enable a feeding of stopper rods into the kiln from the outside or a circulation within the kiln.

In accordance with the invention, the station where the covering is knocked off is provided with an approximately hemicylindrical bowl, which conforms to the stopper rod and is faced on its concave side by a chisel, which is operable by a compressed air cylinder. Because the station where the covering is knocked off is within the range of the rod-handling device, the latter may be used not only to move the rod to the station where the covering is knocked off but also to impart a vertical movement to the rod as the covering is knocked off. It will be sufficient to arrange the hemicylindrical bowl, which serves as an abutment, and the chisel on fixed levels and to move the stopper rod suspended from the rod-handling device throughout this operation up and down by the rod-handling device so that the covering which has been knocked off falls into a bin or the like placed in a suitable pit.

Stopper rods which have become bent must be straightened before they are covered and reused. For this purpose, a straightening bed which can be erected from a horizontal position is provided in accordance with the invention at the rod-straightening station and comprises a jib arm, which is displaceable along the bed and serves for lifting the roller block, connected to the stopper rod, from the guide rail and for applying said roller block to the guide rail, said bed carries a carriage carrying a straightening hammer which is operable by a cylinder-piston unit, and the bed also carries adjustable holder-ups for engaging the stopper rod. When a stopper rod is to be straightened, the straightening bed is erected and the jib arm engages the stopper rod below the roller block and lifts the stopper rod from the guide rail, whereafter the straightening bed and the stopper rod received by it are lowered to a horizontal orientation. The rod now rests on the holder-ups and can be straightened by means of the straightening hammer mounted on the carriage whereas the holder-ups are correspondingly adjusted. It will be understood that the stopper rods may be straightened by hand. When the stopper rod has been straightened, the straightening bed is raised and the stopper rod and the roller block secured to it are transferred back onto the guide rail by means of the jib arm so that manual work is hardly required for these operations.

A beam which can be tilted up is provided in the station where the covering is applied and said beam carries a support for the tubular bricks and a jib arm which is displaceable along the beam and which engages each stopper rod, lifts it from the guide rail, and, after lowering of the beam, inserts the stopper rod into the supported bricks. An adjustably mounted rod-backing roller is provided adjacent to that end portion of the brick support which faces the jib arm. Hence, the station where the covering is applied is similar in structure to the rod-straightening station. The jib arm which is longitudinally displaceable on the beam, however, does not only serve to lift the stopper rod and the roller block secured thereto from the guide rail and to apply the stopper rod to said rail, but also to introduce the rod into the tubular bricks until the screw-threaded tip of the rod protrudes from the last tube. The stopper head is then screwed onto the tip. The backing roller serves to facilitate the insertion of the long rods into the first brick of the covering. To prevent a pushing of the bricks from their support as the rods are inserted into the bricks, the tubular brick through which the rod moves last may be held in position by a clip or the like.

The invention is illustrated by way of example in the drawing, in which

FIG. 1 is a diagrammatic top plan view showing a plant for removing, covering and inserting the stopper rods of steel-casting ladles,

FIG. 2 is an elevation showing a rod-handling device and a resting ladle,

FIG. 3 is an enlarged top plan view showing as a detail that end portion of the rod guide of the ladle which engages the stopper rod,

FIG. 4 is an elevation showing a station where the covering is applied,

FIG. 5 is a vertical sectional view showing a roller block applied to the guide rail and

FIG. 6 is an elevation showing a roller block provided with a stopper rod.

FIGS. 7 and 8 are, respectively, a top plan view and a side elevation showing a station where the covering is knocked off.

FIG. 9 is a side elevation showing a rod-straightening station.

The installation according to the invention comprises a resting station 1 for the ladle 2, a rod-handling device 3, a knocking-off station 4, a station 5 for straightening the stopper rods, a station 6 for applying a covering and a drying kiln 7, also a guide rail 8 which extends from its receiving end 9 disposed within the range of the rod-handling device 3 to the stations 5 and 6 and enters the kiln 7. The guide rail 8 has a suitable gradient from the receiving end 9 to the end where it enters the kiln 7. The kiln 7 is provided with a rod-circulating

device, which comprises an endless chain 10, provided with driver flights 11, and a circulation rail 12. Barriers 14 are provided at the guide rail 8 before the station 5 and the station 6 and before the entrance to the kiln. Each barrier 14 is operable by a cylinder-piston unit 13. A rail point 16, which is also shiftable by a cylinder piston unit 15, is provided where the guide rail 8 enters the drying kiln 7.

In accordance with FIG. 2, the ladle 2 contains a stopper rod 17, which is covered by tubular bricks 18 and at its tip carries a stopper 19. The stopper rod 17 is held in the ladle 2 by a rod guide 20, which has a free end portion consisting of arms 21, which can be swung apart and in their closed position are connected by a wedge 22. The two arms embrace the stopper rod 17, which is additionally held by two nuts 23 forced against the ends of the arms.

When a stopper rod 17 is to be removed because its covering must be renewed, a trolleylike roller block 24 is fitted onto the upper end of the rod. A spring-loaded locking bolt 25 is mounted in the block 24 and adapted to snap into a transverse bore 26 of the rod to fix the roller block 24 to the end portion of the rod. When the roller block 24 has been fixed to the rod, the latter is released from its guide and the rod-handling device engages the upper end portion of the rod. This rod-handling device comprises a platform 27, which is provided with rollers which roll on a square-section column 28, along which the platform 27 can be moved up and down by means of a chain drive 29. The column 28 can be rotated about its longitudinal axis by a drive unit 30. The platform 27 can be raised to lift the stopper rod 17 from the ladle. The column 28 can be rotated to impart a pivotal movement to the platform 27 so that the rod 27 is moved to the knocking-off station 4. FIGS. 7 and 8 show that the station 4 comprises an approximately hemicylindrical bowl 33, which conforms to the stopper 17 or

its covering 18 and is disposed above a pit 31 provided with a waste bin 32. A chisel 35 is operable by a compressed air cylinder 34 faces the concave side of the bowl 33. During the movement of the chisel, the stopper rod 17 is gradually lowered with the aid of the platform 27 so that the bricks 18 are knocked off throughout the length of the rod. When the bricks have thus been removed from the rod 17, the latter is moved to the receiving end 9 of the guide rail 8 by a continued movement of the platform 27 and at said receiving end 9 the roller block 24 is placed onto the guide rail 8 whereafter the gradient of the guide rail automatically causes the rod to move to the barrier 14 preceding the rod-straightening station.

The station 5 comprises a straightening bed 38, which is adapted to be erected by a pivotal movement about a horizontal axis 37 by a cylinder-piston unit 36 which is provided with a jib arm 40, which by means of a cylinder-piston unit 39 is adjustable in the longitudinal direction of the bed. The bed carries a carriage 41, which is provided with a straightening hammer 42, and the bed also carries adjustable holder-ups 43. When it is desired to straighten a rod 17, the bed 38 is erected and the jib arm 40 is operated to engage the rod 17 between the two nuts 23 and to lift the rod 17 from the guide rail 8. The bed is then lowered to the position shown in FIG. 9 and the rod is straightened by means of the hammer 42 and the holder-ups 43. When the rod has been straightened, the bed 38 is swung up once more and the jib arm 40 is operated to apply the rod 17 back to the guide rail 8. The roller block from which the rod is suspended now moves along the guide rail to the station 6 or the barrier 14 preceding the station 6. To

avoid an excessive impact between roller blocks 24 is two or more roller blocks accumulate before a barrier, the roller blocks 24 are provided with rubber buffers 24a (FIG. 6) on their leading and trailing end faces.

The station 6 (FIG. 4) where the covering is applied comprises a beam 45, which is adapted to be tilted up by a cylinder-piston unit 44 and on which a jib arm 46 is mounted to be longitudinally displaced by means of an endless driving chain 47. The beam 45 is also provided with a support 48 for the covering bricks 18. The support 48 is preceded by a backing roller 50, which is mounted on a pivoted arm 49.

When the beam 45 has been tilted up, the jib arm 46 receives the rod 17 from the guide rail 8, just as the jib arm 40 of the straightening bed 38 receives the rod in the rod-straightening station. As soon as the beam 45 has returned to its horizontal position, the jib arm 46 is extended until the support for the bricks is freely. The required new covering bricks 18 are now placed onto the support and the outermost brick is held in position by a clip 51 or the like. The jib arm 46 is then retracted to push the rod 17 through the tubular bricks 18. In this operation, the roller 50 facilitates the insertion of the rod into the first brick. The rod 17 is inserted to such an extent that its screw-threaded tip protrudes from the last brick 18 and the stopper 19 can be screwed to said tip. The clip 51 or the like is now disengaged and the beam 45 is tilted up and the covered rod 17 is applied back to the guide rail 8, along which the rod is moved into the drying kiln 7 with the aid of the roller block. When the rod has moved through the kiln and the bricks have been dried, the rod is received by the platform 27 of the rod-handling device 3 and by said device is moved to the ladle 2, whereafter the platform 27 is lowered to insert the rod into the ladle. Thereafter, the rod guide 20, 21 is applied and the roller block 24 is removed.

It will be understood that the invention is not restricted to the embodiments shown by way of example and that changes in design are possible within the scope of the invention. For instance, the cylinder-piston units and chain drives may be replaced by different means.

What is claimed is:

1. An installation for removing a stopper rod from a ladle, applying a new covering to said stopper rod and reinserting the stopper rod into the ladle, which installation comprises a resting place for a ladle,

a knocking-off station for knocking off a refractory covering from a stopper rod,

a drying kiln provided with a circulating device, an inclined guide having a receiving portion and leading into said drying kiln, and

a rod-handling device which is horizontally and vertically movable with a predetermined range, which includes said resting place, knocking-off station, drying kiln, and receiving portion,

said installation further comprising adjacent to said guide a rod-straightening station and a station for applying a refractory covering to said stopper rod.

2. An installation as set forth in claim 1, in which a column is provided and

said rod-handling device comprises a platform which is mounted on said column to be movable up and down along said column and to be pivotally movable about the axis of said column.

3. An installation as set forth in claim 1, in which said guide comprises a guide rail.

4. An installation as set forth in claim 3, which comprises a trolleylike roller block which is adapted to be fixed to the upper end portion of the stopper rod and to be applied to and roll along said guide rail.

5. An installation as set forth in claim 4, in which said stopper rod is provided in its upper end portion with an

interlocking means, and
said roller block is adapted to be fitted on said upper end portion of said stopper rod and comprises a spring-loaded locking bolt, which is movably mounted and adapted to interengage with said interlocking means.

6. An installation as set forth in claim 5, in which said interlocking means comprises a transverse bore.

7. An installation as set forth in claim 4, which comprises three barriers, which are provided at said guide rail and respectively precede said rod-straightening station, said station for applying said refractory covering and said drying kiln, said barriers being adapted to intercept said roller block on said guide rail.

8. An installation as set forth in claim 7, in which each of said barriers is provided with a cylinder-piston unit, which is operable to move the respective barrier into a position to intercept said roller block on said guide rail.

9. An installation as set forth in claim 4, in which said roller blocks have leading and trailing ends provided with cushioning means.

10. An installation as set forth in claim 9, in which said cushioning means comprise rubbers buffers.

11. An installation as set forth in claim 4, in which said rod-straightening station comprises

a straightening bed which is pivotally movable between a horizontal position and a raised vertical position, a jib arm carried by said bed and displaceable along said bed to lift said roller block from said guide rail and to lower said roller block onto said guide rail when said bed is in said raised position,

a carriage carried by said bed, a straightening hammer which is carried by said carriage, a cylinder-piston unit which is carried by said carriage and adapted to operate said hammer, and

adjustable holder-ups carried by said bed and engageable with said stopper rod.

12. An installation as set forth in claim 3, which comprises a rail point where the guide rail enters the drying kiln.

13. An installation as set forth in claim 1, in which said knocking off station comprises

an approximately hemicylindrical bowl, which conforms to the stopper rod,

a chisel which faces the concave side of said bowl, and a compressed air cylinder for operating said chisel.

14. An installation as set forth in claim 1, in which said station for applying a refractory covering comprises

a beam adapted to be pivotally erected,

a support carried by said beam and adapted to support tubular refractory bricks,

a jib arm which is mounted on said beam for movement along the same, said jib arm being adapted to engage a stopper rod, lift it from said guide rail, and, after a lowering movement of said beam, to insert said rod through bricks placed on said support, and

a rod-backing roller adjustably mounted on said beam adjacent to that end of said support which is adjacent to said jib arm.
